UNITED STATES PATENT OFFICE.

HAAKON P. LINDBACK, OF MINNEAPOLIS, MINNESOTA.

BOOK-COVER CLEANER.

1,370,657.

Specification of Letters Patent.

Patented Mar. 8, 1921.

Application filed June 11, 1919. Serial No. 303,445.

To all whom it may concern:

Be it known that I, HAAKON P. LINDBACK, a citizen of the United States, residing at Minneapolis, in the county of Hennepin and State of Minnesota, have invented certain new and useful Improvements in Book-Cover Cleaners; and I do hereby declare the following to be a full, clear, and exact description of the invention, such as will enable others skilled in the art to which it appertains to make and use the same.

Particularly, my invention has for its object to provide a simple and efficient machine for rapidly and efficiently removing surplus metal foil from book covers after titles, and the like, have been printed thereon by the use of such metal foil. Generally stated, the invention consists of the novel devices and combinations of devices hereinabove described and defined in the claims.

In the accompanying drawings which illustrate the invention, like characters indicate like parts throughout the several views.

Referring to the drawings:

Figure 1 is view in plan with some parts broken away and some parts sectioned, showing the improved machine;

Fig. 2 is a vertical section taken approximately on the line 2—2 of Fig. 1;

Fig. 3 is an enlarged vertical section on the line 3—3 of Fig. 2, some parts being broken away;

Fig. 4 is a horizontal section on the line 4—4 of Fig. 3; and

Fig. 5 is a detail in section through the brush on the line 5—5 of Fig. 1, some parts of the same being removed.

The various parts of the machine are carried directly, or indirectly, on a marginal hollow base 6 formed with a large rectangular opening at its top, and in which is fitted a rectangular table 7. This table 7 is adjustably supported from the cross bar 8 located just above the lower edges of the flanges of the frame 6, and to which, at its ends, it is bolted, or otherwise, rigidly secured. For an important reason, the table 7 is made vertically adjustable by a device best shown in Fig. 3. This device comprises two telescoped sleeves 9 and 10 having end flanges rigidly secured, respectively to cross bar 8 and to the table 7. The numeral 11 indicates an adjusting screw that is passed through the sleeve 10 and has threaded engagement at its lower end at 12 with lower

end portion of sleeve 9. A pin 13 driven through an eccentric hole in sleeve 10 engages an annular groove 14 in screw 11 so that the said screw, while free for rotation in respect to sleeve 10 and table 7 will, nevertheless, carry the said elements 10 and 7 vertically with it. The head of screw 11 is exposed to the top of table 7 but is flush with the upper surface thereof.

To hold the table 7 against rotation with screw 11 when said table is raised out of the opening in frame 6, a dowel pin or guide stud 15 is secured to bar 8 and engages a notch in the rear edge of the said table.

Extended across the front portion of table 7 but spaced a considerable distance above the same, is a shaft 16 which, at one end, is connected to, or forms an extension of the armature shaft of a small electric motor 17 that is mounted on an extended portion 6a of bed frame 6. At its other end, shaft 16 is journaled in an arm 18 that is spaced from one side and extends rearward over the bed frame 6, and, at its rear end, has a flange 18a bolted, or otherwise rigidly secured to said frame.

Shaft 16 carries a brush and a buffing roller for purposes which will be presently noted. Said brush may be of any suitable construction, but, as shown, it comprises a plurality of bristle-equipped bars 19 carried by flanged heads 20 rigidly secured to said shaft 16. Buffing roller 21 has a pliable buffing face 22 of soft cotton or other suitable material.

For carrying off the dust or metal fiber loosened up by the cleaning brush, a light sheet metal hood 23 is extended from a point immediately above said brush, rearward to the rear portion of frame 6, where it is joined to a suction tube 24 that leads to a fan casing 25 mounted on the rear portion of said frame 6. Fan case 25 is provided with a discharge spout 26 that leads to a suitable port for the discharge or collection of the metal dust.

Hood 23 is open at its inner side and suction tube 24 is open at its front side, so that dust or metal particles will be drawn into the eye of the fan, substantially on lines indicated by arrows marked on Fig. 1, both from the brush and from the buffing roller.

Working within the fan casing 25 is a fan head 27, the shaft of which projects at 110

one end and, as shown, is provided with a small grooved pulley 28. A belt 29 runs over pulley 28 and over a similar pulley 30 on the shaft 16, so that said fan will 5 be driven directly from the motor 17.

Book covers will vary in thickness and, moreover, the brushes and the buffing roller will run down to smaller diameter, and hence the necessity for vertical adjustments 10 of the table 7. A book cover is indicated by the character *b* in Fig. 2.

After the title or other matter has been printed on the book cover in the usual way by the use of metal foil, portions of the 15 foil between and around the letters and characters must be removed, but this has usually been done by hand and is a slow tedious operation. By the use of this improved machine, the removal of the surplus 20 foil can be quickly and properly removed in a very efficient manner. The table 7 should be vertically adjusted so that when a book cover is placed thereon and moved under the brush or under the buffing roller, 25 the printed surface of the cover will be lightly engaged by the brush or buffing roller, as the case may be.

For the removal of the foil, the brush is used, and as this is being done, the removed 30 foil will be drawn into the fan casing and discharged therefrom under the action of the fan. After the surplus foil has been removed, a polish may be given to the surface of the letters and the cover further 35 cleaned by moving the cover under the buffing roller while in flat engagement with the table 7.

The efficiency of this device has been demonstrated in practice.

What I claim is:

1. In a device of the kind described, the combination with a marginal bed frame, of a table mounted in an opening thereof, a brush working above said table, and means for vertically adjusting said table in respect 40 to said brush, said means comprising telescoped inner and outer sleeves, the former being secured to said table and the latter being anchored in respect to said bed frame, a screw exposed through the table at its upper end, extended down through and swiveled to the inner sleeve and having threaded engagement with the base of the outer sleeve.

2. In a device of the kind described, the combination with a marginal bed frame, of a table mounted in an opening thereof, a brush working above said table, means for vertically adjusting said table in respect to 45 said brush, said means comprising telescoped inner and outer sleeves, the former being secured to said table and the latter being anchored in respect to said bed frame, a screw exposed through the table at its upper end, extended down through and swiveled to the inner sleeve and having threaded engagement with the base of the outer sleeve, and a dowel pin anchored in respect to 50 said bed frame and engageable with said table to hold the same against rotation while 55 free for vertical adjustments.

In testimony whereof I affix my signature in presence of two witnesses.

HAAKON P. LINDBACK.

Witnesses:

CLARA DEMAREST,
BERNICE G. BAUMANN.
